ICE CREAM CONTAINER

Albert H. Rhody, Flint, Mich.

Application September 26, 1939, Serial No. 296,657

2 Claims. (Cl. 206—56)

This invention relates to ice cream containers and has for an object to provide a device of this character which will comprise an outer package of cylindrical formation and a plurality of inner 5 containers of substantially sector formation nested within the outer package so that freezing of the ice cream while in the container may be effected, and the frozen ice cream kept sanitary and later conveniently and easily distributed at 10 picnics and other places.

A further object is to provide a device of this character in which the sector shaped containers will be provided with spoons the handles of which are disposed at the center of the cylindrical outer 15 package to form grips by means of which the containers may be removed individually after one of the containers is removed by punching it up with the finger inserted through a hole in the bottom of the package.

20 A further object is to provide a device of this character which will be formed of a few strong simple and durable parts, which will be inexpensive to manufacture and which will not easily get out of order.

25 With the above and other objects in view the invention consists of certain novel details of construction and combinations of parts hereinafter fully described and claimed, it being understood that various modifications may be resorted to 30 within the scope of the appended claims without departing from the spirit or sacrificing any of the advantages of the invention.

In the accompanying drawing forming a part of this specification:

35 Figure 1 is a plan view of an ice cream container constructed in accordance with the invention.

Figure 2 is an enlarged longitudinal sectional view of the ice cream container taken on the line 40 2—2 of Figure 1.

Figure 3 is a perspective view of one of the sector shaped containers.

Figure 4 is a perspective view of one of the sector shaped containers with the cover removed.

45 Figure 5 is a detail perspective view of the cover of a sector shaped container showing the same crimped to prevent dislodgment, and showing a spoon carried thereby.

50 Referring now to the drawing in which like characters of reference designate similar parts in the various views, 10 designates an outer package of cylindrical formation, open at the top and formed of any suitable material. A plurality of inner containers 11 of substantially sector formation are nested within the outer package with their smaller ends terminating short of the center of the outer package to provide a central space as best shown in Figure 1.

A cover 12 is provided for each sector shaped container having a flange 13 adapted to fit down over the outside of the wall of the container, and terminating short of the small end of the container. The flange is crimped as shown at 14 in 5 Figure 4, at the corners of the wide end of the cover to provide frictional gripping means for engaging the wall of the container and preventing dislodgment of the cover.

A spoon 15 of the same material as the container, or of different material as desired, is inserted underneath the cover with the handle 16 projecting through the open small end of the flange 13. The handles of the spoons all project 15 into the central space between the sector shaped containers so as to be easily gripped for removing the containers individually from the package after one container is removed.

To permit removal of the initial container an opening 17 is formed in the bottom of the outer 20 package. The fingers of the operator may be thrust up through this opening against the bottom of the overlying sector shaped container to force the container upwardly out of the package as best shown in Figure 2.

25 It will be pointed out that the package and containers therein will occupy but small space and also that the ice cream may be frozen in the containers while nested within the package. The sector shaped containers maintain the ice cream 30 in a sanitary condition until the containers are removed for use at picnics and other places.

From the above description it is thought that the construction and operation of the invention will be fully understood without further explanation.

What is claimed is:

1. A container comprising an outer package of cylindrical formation, inner packages of sector formation nested within the outer package with 40 their smaller ends terminating short of the center of the outer package to provide a central space, covers on the containers, and spoons located below the covers and having their handles projecting beyond the smaller ends of the containers into said space.

2. A container comprising an outer package of cylindrical formation, inner containers of sector formation nested within the outer package, there being an opening in the bottom of the outer 50 package permitting one of the containers being dislodged upwardly from the package, the smaller ends of the containers terminating short of the center of the outer package to provide a central space, covers for the containers, and spoons in 55 the containers below the covers having handles projecting into said space.

ALBERT H. RHODY.
